ALARM DEVICE

Benjamin F. MacPherson, San Francisco, Calif.

Application June 29, 1939, Serial No. 281,970

3 Claims. (Cl. 161—22)

This invention relates to improvements in alarm devices and especially is concerned with a new and improved substantially silent alarm device useful in arousing the sleeping deaf or for 5 other similar purposes where silent alarm for arousing sleepers is to be preferred.

It is an object of the present invention to provide a silent alarm device which can be mounted near a sleeper's bed and which, when 10 functioning, will serve not unpleasantly to arouse the sleeper without discomfort, noise or shock.

Another object of the present invention is to provide an alarm device comprising means for physically annoying a sleeper whereby arousing 15 the sleeper but doing so in a manner which does not promote the sleeper's discomfort and which may function irrespective of the position occupied by a sleeper on the bed and also irrespec- 0 tive of the locality of the bed wherein the sleeper rests.

Another object of this invention is to provide in an alarm device a source of continuous annoyance to a sleeper whereby the sleeper effectually is aroused but preferably is aroused 25 neither with suddenness nor with shock.

A feature of the device according to the instant invention is its simplicity of construction and of operation which, firstly, suits it well to the requirements of mass production, and which, sec- 30 ondly, diminishes the likelihood of failure during use and the cost of repair.

An advantage of the novel alarm device according to the instant invention is that the portions of the device which come in physical contact with the person to be awakened may be removed from the device for purposes of sterilization or treatment.

Other objects, advantages and features of the novel device according to this invention will be 40 apparent to those skilled in this art during the course of the following description.

Regarded in certain of its broader aspects the substantially silent device according to the present invention comprises an upright standard attachable to side portions of the bed and carrying in centrally located parts thereof a pivotally mounted vertically swinging member carrying ticklers which, when the member is in lowered or in essentially horizontal position, overlie the 50 portions of the bed normally occupied by the head of the sleeper, thereby doing annoyance to and causing the awakening of a sleeper in said bed, and time controlled means for lowering said member from raised into horizontal position at a preselected time.

In order to facilitate a fuller and more complete understanding of the matter of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the subjoined claims. 10

Referring then to the drawing,

Figure 1 is a perspective view illustrating the preferred embodiment of the present invention in use.

Fig. 2 is essentially a side elevational view of 15 the presently preferred embodiment of the instant invention, and

Fig. 3 is a front elevational view of the device shown in the foregoing figures. 20

Referring now especially to Figs. 1 and 2, it will be noted that the alarm device generally designated by the numeral 10 comprises an essentially upright standard 11 having attached near the bottom portion 11a thereof arms 12 carrying threaded screws 13 received in tapped 25 openings formed in the arms 12 and provided with clamp faces 13b and wing nuts 13a for facilitating rotation of the screws. It will be evident that the arms, together with the screws, provide clamps by means of which the bottom portion 30 11a of the standard 11 may be clamped upon side parts of the bed A for holding the standard in essentially upright position adjacent the side of the bed.

A vertically swinging member 14 mounted at 35 one end of the central portion 11b of the standard 11 by means including the hinge elements 15 extends horizontally outwardly from the standard essentially as shown being supported in horizontal position by means of the projecting 40 bracket 16 attached to the standard beneath the place of mounting of the member 14. Downwardly extending ticklers 17 are mounted on the under-surface of the member 14 as by means of hooks and loops where, if desired, the ticklers 45 17 may be removed for sterilization.

A relatively inextensible substantially flexible cable 18 attached to distal parts of the member 14, as for instance by means of the eye 19, passes upwardly through a freely rotatable pulley 20 50 mounted upon the upper portion 11c of the standard 11 and is wound about and attached to a spool 21, rotatable periodically by the clock 22 mounted on the shelf 23. Latch means 24, such as a conventional hook and eye, are provided for

holding the member 14 in raised position as shown in phantom in Fig. 2.

Having thus described the preferred embodiment of the present invention, its mode of operation herein will be related. The device is mounted upon a side bar A' of a bed A as hereinbefore mentioned whereby the standard extends in substantially upright position next the bed in a manner such that the member 14, when lowered, overlies and is suited to do annoyance to sleepers in the bed. In setting the device for use the spool 21 is rotated whereby the portion of the cable 18 is stored thereon and the member 14 is moved into the position shown in phantom in Fig. 2. In other words, the member 14 is moved into raised but slightly inclined from the vertical position. At such preselected time as the clock 22 is set to function, the spool 21 rotates, unwinding the cable 18 and permitting the member 14 to descend by action of gravity into essentially horizontal position as depicted whereby the dependent ticklers 17 do annoyance to and arouse sleepers thereunder.

Having thus described the present invention, what it is desired to secure by Letters Patent is:

1. An essentially silent alarm device comprising a supported standard; a pivotally mounted downwardly swinging member attached to said standard adapted to overlie portions of a bed when the standard is positioned thereagainst; ticklers carried on said member for annoying and awakening a sleeper when the member is in horizontal position; and means for holding the member in raised position comprising a relatively inextensible cable attached to one end to distal parts of the member, a time controlled power driven spool mounted on the standard near the top thereof to which the free end of the cable is attached in a manner such that rotation of the spool causes the member to be raised or lowered.
2. A substantially silent alarm device comprising a standard; a horizontally positionable mem-

ber pivotally mounted centrally on said standard swingable upwardly thereagainst; ticklers freely downwardly extending from said member for annoying a sleeper when the member is in horizontal position; means for holding said member in raised position comprising a relatively inextensible cable attached at one end to distal parts of said member, a pulley mounted on said standard near the top thereof for receiving said cable, a time controlled power driven spool mounted on said standard near the top thereof to which the free end of said cable is attached in a manner such that rotation of said spool causes said cable to travel over said pulley raising or lowering said member; and a latch for retaining said member in raised position.

3. A substantially silent alarm device comprising a standard; a clamp mounted on said standard engageable with side portions of a bed for holding said standard thereagainst in essentially upright position; a horizontally positionable member pivotally mounted centrally on said standard swingable upwardly thereagainst; ticklers freely downwardly extending from said member for annoying a sleeper when the member is in horizontal position; means comprising a projecting bracket mounted on said standard beneath the place of mounting of said member for limiting the downward swinging motion of said member; means for holding said member in raised position comprising a relatively inextensible cable attached at one end to distal parts of said member, a pulley mounted on said standard near the top thereof for receiving said cable, a time controlled power driven spool mounted on said standard near the top thereof to which the free end of said cable is attached in a manner such that rotation of said spool causes said cable to travel over said pulley raising or lowering said member; and a latch for retaining said member in raised position.

BENJAMIN F. MACPHERSON.
